(57) CLAIM

The ornamental design for an article of clothing, as shown and described.

DESCRIPTION

FIG. 1 is an enlarged perspective view of an article of clothing showing the claimed design.

FIG. 2 is front view thereof; and,

FIG. 3 is another front view thereof.

The broken lines, immediately adjacent to the full lines and shaded areas, in FIGS. 1-3, represent the boundary of the design and form no part of the claim.

1 Claim, 3 Drawing Sheets

FIG. 3
